UNITED STATES PATENT OFFICE.

ISAAC A. ROMMER, OF BROOKLYN, NEW YORK.

WALKING TOY.

1,414,210.

Specification of Letters Patent. Patented Apr. 25, 1922.

Application filed October 5, 1920. Serial No. 414,744.

To all whom it may concern:

Be it known that I, ISAAC A. ROMMER, a citizen of the United States, and a resident of the city of New York, borough of Brooklyn, in the county of Kings and State of New York, have invented a new and Improved Walking Toy, of which the following is a description.

My invention relates to walking toys, such as dolls, animal figures, and the like, and more particularly the invention relates to the means for pivotally attaching the legs in a manner so that as one leg moves forwardly the other is moved backward.

The general object of the invention is to provide new pivotal means for the legs as well as a novel manner of linking up the one leg with the other to give the correlated movements.

Reference is to be had to the accompanying drawings forming a part of this specification, it being understood that the drawings are merely illustrative of one example of the invention.

Figure 1 is a side elevation of a walking toy embodying my invention, indicating the left leg forward and the right leg in a relative rearward position;

Figure 2 is a view similar to Figure 1 showing the reverse position of the legs after a forward movement of the right leg;

Figure 3 represents the figure in sitting posture;

Figure 4 is a vertical section taken at the connection between the pivots of the respective legs, the parts corresponding in position to those of Figure 1;

Figure 5 is a view similar to Figure 4 with the parts corresponding with Figure 2;

Figure 6 is a view similar to Figure 5 with the parts corresponding in position with Figure 3;

Figure 7 is an enlarged horizontal section at the pivots.

In the drawings A represents a torso of a walking doll; B, the right leg; and B', the left leg.

In accordance with my invention I provide for the respective legs, B, B', separate transverse pivot rods 10 and 11 which pass through the torso in opposite directions, the one 10 projecting at one side sufficiently to receive the leg B' and the other 11 projecting sufficiently at the other side of the torso 55 to receive the other leg B. In order to link up the pivot rods at one side a suitable con-

nection is effected therebetween, the illustrated means comprising a hook 12 on the one link, the other rod 11 being bent at right angles as at 13 adjacent to an end 60 thereof so that the terminal 11^a is offset to lie in a plane parallel with the body or major portion of said pivot rod, said offset end being engaged by said hook 12. The projecting ends 10^a 11^a of the respective rods are 65 threaded to receive nuts 14, 15 at the outer sides of the legs to retain the latter in position but free to swing. Rod 11, at the opposite end from offset terminal 11^a has a nut 16. It will readily be understood that the 70 illustrated arrangement involves merely a convenient expedient for the purpose of holding the legs frictionally on their respective pivot rods so that a leg will turn with its rod and vice versa through a limited 75 arc, but at the same time the legs may be turned on the rods to a further extent to dispose the toy in sitting posture.

Suitable spacers 17 are disposed on the rod, 10, at opposite sides of the torso, between the latter and the legs. Also, various washers and wear elements may be included in the structure, the arrangement shown being as follows: On the rod 10 at the outer side beneath the nut 14 is a washer 18, the 80 rod 11 at the opposite side of the doll outside of the leg having a washer 19, and a washer 20 is on the rod 10 at the inner side of the one leg, while a concave washer 21 is employed at the inner side of the opposite leg 90 adjacent to the hook 12 so that the latter is within the plane of the inner side of the leg, between said concave washer and the right angular bend 13 of the opposite leg. Similarly, a wear disk 22 may be employed 95 beneath the washer 19, and a wear disk 23 beneath the washer 20. On the torso A at the pivot rods are bar washers or disk washers 24 through which both pivot rods 10, 11 pass as well as wear plates 25 beneath 100 said washers 24.

It will be clear from the above description and from the drawings, particularly Figures 4 to 7, that the connection between the pivot rods of the respective legs through the medium of the hook 12 and offset end 11^a, will cause a forward movement of the one leg to impart a rearward movement to the other leg. Also, the described connecting up of the rods limits the swinging 110 movement thereof since the movement is limited by the arcuate paths through which

the hook 12 and offset end 11^a may turn. The separate pivoting of the legs simplifies the linking up of the same and makes for a strong and simple construction as well as 5 for the unfailing reciprocal relation of the legs.

I would state in conclusion that while the illustrated example constitutes a practical embodiment of my invention I do not 10 limit myself strictly to the mechanical details herein illustrated, since manifestly the same can be considerably varied without departure from the spirit of the invention as defined in the appended claims.

15 Having thus described my invention, I claim:

1. A toy of the class described including a body, approximately parallel transverse rods rockably mounted in the body, legs at 20 the opposite sides of said body and frictionally held to the adjacent ends of the rods to swing to a limited extent with said rods and movable to a further extent relatively to said rods to give the toy a sitting posture, and a connection between said rods 25 so that a rocking movement of one will impart a reverse rocking movement to the other.

2. A walking toy of the class described, including a body, separate pivot rods extending transversely through said body and

projecting respectively at opposite sides thereof, the one rod having its projecting end offset, the other of said rods having a member linked up with said offset end, and legs on the projecting end of each rod. 35

3. A toy of the class described including a body, approximately parallel transverse rods rockably mounted in the body, legs at the opposite sides of said body and frictionally held to the adjacent ends of the rods to 40 swing to a limited extent with said rods and movable to a further extent relatively to said rod to give the toy a sitting posture, and means directly connecting said rods to cause a movement of one to impart a reverse movement to the other, 45

4. A toy of the class described including a body, legs at the sides of the body, and separate means carrying the respective legs and rockably mounted on the body to turn 50 about different centers, said legs being frictionally held on said means to swing therewith to a limited extent, the legs being movable to a further extent relatively to said rods for giving the toy a sitting posture, 55 said leg carrying means being directly connected so that a movement of one imparts a reverse movement to the other.

ISAAC A. ROMMER.
